US00D669549S

(12) **United States Design Patent** (10) **Patent No.:** **US D669,549 S**
Titley et al. (45) **Date of Patent:** **** Oct. 23, 2012**

(54) **SURF OR PADDLE BOARD**

(75) Inventors: **Michael William Titley**, Elmsworth (GB); **Peter Bladd-Symms**, Storrington (GB)

(73) Assignee: **Envior Limited**, Hampshire (GB)

(**) Term: **14 Years**

(21) Appl. No.: **29/418,985**

(22) Filed: **Apr. 24, 2012**

(30) **Foreign Application Priority Data**

Oct. 24, 2011 (EM) 001299879-0001

(51) **LOC (9) Cl.** **21-02**

(52) **U.S. Cl.** **D21/769**

(58) **Field of Classification Search** D21/769-770, D21/801, 803, 809; 114/253, 345-346; 441/35, 441/66, 74, 40-42, 129-132; 472/128-129; D12/5, 6, 316
